UNITED STATES PATENT OFFICE.

OWEN HAWKINS, OF GLOBE, ARIZONA.

OIL-SEPARATOR.

1,312,324.

Specification of Letters Patent.

Patented Aug. 5, 1919.

Application filed March 12, 1919. Serial No. 282,098.

To all whom it may concern:

Be it known that I, OWEN HAWKINS, a citizen of the United States, residing at Globe, in the county of Gila and State of 5 Arizona, have invented a new and Improved Ore-Separator, of which the following is a full, clear, and exact description.

This invention generally relates to a new and improved means for separating or classifying material according to various sizes. 10 In the present application it is more particularly for use in the milling and concentrating of mineral ores. It has for one of its objects the provision of a means whereby 15 the materials may be more readily and thoroughly separated.

Another object is to provide an improved method for use in that class of separators in which the crushed or ground ore is fed to 20 a screen member with water or other liquid, the under-sized material and liquid passing through said screen and the over-sized material being retained and collected above said screen. Heretofore there has been a tendency 25 for the screens to become blinded or clogged, thus permitting a considerable portion of the under-sized material to be carried away with the over-sized material and so preventing a proper separation.

Another object of this invention is to 30 overcome the above objection and provide a means which precludes the possibility of the screen becoming blinded or clogged, thus affording a means whereby practically all 35 of the undersized material will be separated from the over-sized material.

By "under-size" is meant that material which will pass through the openings of the screen, and "over-size", that which is too 40 large to pass therethrough.

In order to accomplish the above-named objects there is provided an inclined screen member reciprocating longitudinally, and a member located below and coöperating with 45 said screen, so arranged that a series of impinging currents of water strikes the lower side of the screen. In the structure shown there is provided a series of steps arranged beneath the screen, with the intersection of 50 the tread and riser portion spaced from the tread a sufficient distance to permit the downward flow of the water thereover to carry with it the under-sized ore which has passed through the screen. As the water 55 passes over these points of intersection, there is formed a wave or crest of water

which impinges against the lower side of the screening member, part of which water passes therethrough and tends to loosen portions of material which have become clogged 60 in the openings, and carries any remaining portions of under-sized material through the screen as the water again passes downward from the screen to the next successive step. This process is repeated throughout the 65 length of the inclined surface.

In the accompanying drawings, forming part of this specification, similar characters of reference refer to corresponding parts in the several views, in which,—

Figure 1 is a longitudinal sectional view showing the relative arrangement of the feeding hopper, screening member, the means for obtaining the series of impinging currents to same, and the actuating 75 means for effecting the reciprocating longitudinal movement therebetween;

Fig. 2 is a sectional view taken on the line 2—2 of Fig. 1 with supports removed; and

Fig. 3 is a plan view looking down at the 80 upper part of the separator.

In the accompanying drawing the preferred form of my invention is shown as comprising an inner frame member having sides 1 and a screening member 2 connecting 85 the bottom thereof, said inner frame member having bearing blocks 3 suitably secured to the side members thereof, and adapted to slide on guides 4, which are in turn mounted upon the side portions 5 of an outer launder. 90 The said side portions 5 are suitably connected by a connecting member 6. The launder is supported in an inclined position by a frame structure comprising supports 7 and the connecting member 8. Any suitable means is 95 provided for securing the reciprocating longitudinal motion of the inner frame member relative to the outer launder. To effect this movement there is provided a driving member 9 mounted on a crank shaft 10 in bearing blocks 11, which are suitably secured to the stationary side portions 5 of the outer launder. Reciprocating motion is imparted to the inner frame member by means of connecting rod 12 having one end journaled in a 100 bearing 13 which is suitably connected to the inner frame member and the other end with the crank shaft 10.

In the bottom of the outer launder there is provided a series of steps 14, which may be 110 of metal or any other suitable material, comprising a riser 15 and a tread portion 16,

the surface of the tread portion being inclined in such position as to carry the water or other material down the launder. The upper part of the riser is spaced from the 5 lower side of the screen a sufficient distance to permit a certain portion of the water to carry under-sized material therebetween and at the same time permit a certain portion of the water to impinge against the lower side 10 of the screen. In this manner a certain portion of the water will strike the screen with sufficient force to dislodge any portions of material which have become clogged in the screen member, thus keeping the screen open 15 at all times. This process of having the water pass through the screen is repeated a number of times throughout the length of the launder. This, in connection with the longitudinal reciprocating motion of the 20 screen member brings all parts of said screen member under the cleaning effect of these series of waves or falls which are formed by the water flowing over the series of steps. After the water has passed through the 25 screen from the bottom it will also have a tendency to carry with it any remaining under-sized material. It is thus seen that by providing a launder of sufficient length that all of the under-sized material may be carried 30 through the screen and collected at a suitable point 17. The motion of the inner frame member further tends to carry the over-sized material to the bottom of the launder where it may be deposited on receiving 35 members 18.

In operation the crushed or ground material carried in the wash water is fed to the screen member through a hopper 19.

What I claim is:

40 1. In an apparatus of the class described, an inclined frame member, a screen therefor, a series of stepped portions arranged below said screen to cause a plurality of independent currents of water to strike the bottom of 45 said screen member and a means for obtain-

ing relative movement between the screen member and the stepped member.

2. In an apparatus of the class described, an inclined screen member, a series of stepped portions beneath and adjacent to 50 said screen member and means for obtaining a reciprocating movement between the screen member and the stepped portions.

3. In an apparatus of the class described for separating material carried in a wash 55 water, an inclined movable screen member and relatively fixed means spaced below and adjacent to said screen member to cause water flowing thereover to strike the bottom of said screen member.

4. In an apparatus of the class described, a stationary inclined launder, stepped portions therefor, a movable screen member spaced above and adjacent to said steps and a means for obtaining a reciprocating motion 65 of the screen member with respect to the stepped portions.

5. In a separating device for straining crushed ore carried in a liquid, an inclined frame member, a screen therefor, steps 70 spaced from and positioned below said frame member, said steps having the edges thereof separated from the screen a sufficient distance to form as the liquid flows thereover a series of impinging waves or crests 75 which strike the said screen and a means for obtaining relative motion between the said steps and said screen.

6. In a separating device for screening crushed ore carried in a liquid, a frame 80 member, a screen therefor, a trough, steps therefor having the edges thereof separated from the screen a sufficient distance to form as the liquid flows thereover a series of impinging waves or crests which strike the 85 screen and means for obtaining relative motion between the steps and the screen member.

OWEN HAWKINS.

Copies of this patent may be obtained for five cents each, by addressing the "Commissioner of Patents, Washington, D. C."

It is hereby certified that in Letters Patent No. 1,312,324, granted August 5, 1919, upon the application of Owen Hawkins, of Globe, Arizona, for an improvement in "Ore-Separators," an error appears requiring correction as follows: In the grant and in the heading to the printed specification, title of invention, for the words "Oil-Separators" read *Ore-Separators*; and that the said Letters Patent should be read with this correction therein that the same may conform to the record of the case in the Patent Office.

Signed and sealed this 14th day of October, A. D., 1919.

[SEAL.]

M. H. COULSTON,

Acting Commissioner of Patents.
